[57] CLAIM

The ornamental design for a seat, as shown and described.

DESCRIPTION

FIG. 1 is a perspective view of a seat, showing our new design, the broken lines are for illustrative purposes only and form no part of the claimed design;

FIG. 2 is a left side elevational view, the right side being a mirror image thereof;

FIG. 3 is a top perspective view;

FIG. 4 is a front perspective view;

FIG. 5 is a rear perspective view;

FIG. 6 is a bottom plan view;

FIG. 7 is a left side elevational view of an alternate embodiment of our new design, the right side being a mirror image thereof;

FIG. 8 is a front perspective view of the alternate embodiment; and,

FIG. 9 is a top perspective view of the alternate embodiment.
